UNITED STATES PATENT OFFICE

FRANZ OERTEL, OF BERLIN-CHARLOTTENBURG, GERMANY, ASSIGNOR TO WESTING-HOUSE ELECTRIC & MANUFACTURING COMPANY, A CORPORATION OF PENNSYLVANIA

RING SPINNING MACHINE

Application filed June 13, 1929, Serial No. 370,527, and in Germany June 16, 1928.

My invention relates to improvements in ring spinning machines, in which a thread is spun and wound upon a bobbin in the customary manner.

My invention consists of means for controlling the speed of the electric driving motor of a spinning machine which, when commencing to wind, must run at an increasing speed, when winding, at a constant speed, and, when the working process is finished, at a slowly decreasing speed, whereby, according to whether the thread is wound on a small or a large diameter of the bobbin, the speed of the motor and the spindle must slightly vary within this slow increase of the speed, the constant speed and the slow decrease of the speed, in order to equalize the different winding speeds, which are caused by the varying diameters during the winding, according to whether the thread is wound inside or outside on the bobbin.

In practicing my invention, I provide a variable-speed motor adjacent to the spinning machine head. The speed regulation of the motor is effected by a controller. This controller is, according to my invention, connected to a chain wheel or sheave mounted on the usual builder or swing arm by means of a flexible connection, such as a cord, wire or chain. This connection is controlled by means fully described hereinafter.

Further objects of my invention will appear as the specification proceeds.

An embodiment of my invention is illustrated in the accompanying drawing in which,

Fig. 1 is a view, in front elevation, and

Fig. 2 is a view, in side elevation, of my improved spinning machine.

Fig. 3 diagrammatically illustrates the mode of operation of my improved machine, and

Fig. 4 is a curve showing the speed variations, with reference to time, of the motor, brought about by my speed controller.

In the hitherto known speed controllers for ring spinning machines, the adjustment is usually effected by providing special cams or change gears. The construction then becomes complicated and it is not possible to

attain the changes in the speeds necessary when passing from one count of yarn or one raw material to another without exchanging cams, wheels or the like. There are already known spinning controllers in which the regulation of the layers for building the bobbin is directly derived from the builder or swing arm. A flexible connecting member is here employed, which extends from the builder arm to the brush-adjusting lever and is kept taut by the brush-retracting spring. The regulation of the variations from the fundamental speed then takes place in dependence upon the position of the builder arm.

In order to bring about a regulation of the layers also when commencing to wind and when running the yarn off the bobbin when the bobbin building is finished, the flexible connection extending to the brush-adjusting device is, according to my invention, deflected by a special pull member. This pull member is controlled by a crank which, in its turn, is controlled by the ring-rail operating gear. In order to avoid reduction gears, the sheave or chain wheel mounted on the swing or builder arm is preferably employed for transmitting the movement of the crank.

Referring to Figs. 1 and 2 of the drawing, 10 is the head of the spinning machine and 11 the electric driving motor equipped with the brush-shifting device 12. On the builder or swing arm 13 is mounted a sheave 14. From a stationary point on the builder arm a cord 15 extends to a cord grip 16 and over two guide pulleys 17 to the brush-shifting lever of the motor. The brush, retracting spring 18 holds the cord 15 taut. If the builder arm or swing lever 13 traverses the stroke height h , (Fig. 3) and the cord 15 is stretched, the total layer regulation y , (Fig. 4), required for the main spinning is produced. The upper position of the swing arm corresponds to the maximum speed of the motor, and the lower position to the minimum speed.

For the customary bobbin-winding method, the speed rises quickly and the drop in the speed takes place slowly. To enable the peaks in the layer curve to be cut off as

desired, an adjustable stop 19 is provided on the motor frame, which limits the movement of the cord 15.

In order to change the fundamental speed and the amount of the layer regulation when commencing the bobbin building and when running-off the yarn when the bobbin is finished, in the manner shown in Fig. 4 of the drawing, the cord 15 is deflected from its straight path. As shown in Fig. 3 of the drawing, the deflection of the cord 15 may take place down to the point e , so that the layer regulation then practically disappears altogether. This corresponds to the starting point e' of the regulation curve in Fig. 4 of the drawing.

The cord 15 may be deflected by a cord or cable 20 or by a corresponding lever, one end of which is secured thereto and the other end of which is secured to a crank 21. The crank 21 is rigidly fastened to the sheave 22 and is provided with a slot for adjustably connecting the end of the cable 20. The sheave 22 is connected to the sheave 14 by a chain 23. The cable 20 and the crank 21 can thus follow the pull in the direction of the arrow to the extent only in which the chain 23 releases the sheave 22. The chain 23 is released by the sheave 14 mounted on the swing arm step-wise during each stroke by a short distance only. This is effected by the operating mechanism which lifts the ring-rail. The variation of the fundamental speed thus takes place according to the size of the cord-deflecting angle in dependence upon the position of the crank 21.

The disposition of the elements of my invention is such that the lever arm 21 remains substantially motionless during the normal stroke h of the builder arm. This result follows because the sheave 14 is so disposed with reference to sheave 22 that a straight line drawn perpendicularly to the mid-point of a straight line, in a given plane, extending from the points of tangency of chain 23 to sheave 14, when in the two extreme operating positions shown, is tangent to sheave 22 at a point vertically above the axis of sheave 22.

Furthermore, to prevent the possibility of having the speed of the motor periodically and materially varied by the oscillations of the builder arm 13, when the lever 21 is in the broken-line position, the dimensions and disposition of the elements of my invention are so chosen, that a straight line drawn perpendicular to the mid-point of a straight line, in a given plane, extending between the axes of sheave 14, when in the two extreme operating positions shown, passes through point e .

In ring spinning machines, it is customary to drive the sheave or sprocket wheel 14 in such manner that, according to the height of the bobbin, it performs not more than one

revolution. Preferably, the diameter of the sheave 22 and the operative length of the crank 21 are so chosen that the crank pin requires not more than a quarter of a circle to deflect the cord 15 from the straight position down to the point e . At this point, commences the winding of the thread on the bobbin. With such construction of the drivings parts, the duration of the starting period of the bobbin consequently amounts to about a quarter of the entire winding period.

When the stretched position of the cord 15 has been reached, the cable 20 loses its tension by the progress of the crank movement and action upon the layer regulation until the point of attachment of the chain 23 has travelled around the sheave 14 and has entered into the last quarter of its revolution. The deflection of the cord 15 then starts anew to effect the desired drop of fundamental speed and layer regulation for the running-off period. When, after the drawing off is finished, the ring-rail is lowered by means of the handle, the chain-attaching point on the sheave 14 also returns to its initial position.

It is thus obvious that, by means of the mechanism embodying my invention, it is easily possible to effect the variations of the regulation curve required in practice by simple manipulations and without changing any parts. These variations may be produced by displacing the rope grip or clamp 16 connecting the two cords or cables 15 and 20, whereby a change in the proportions of the cord 15 and in the length of the cable 20 is obtained. By varying the radius or the angle of the crank 21, and by adjusting the stop 19, a variation may be attained in the steepness of the pitch of the winding, the duration of the starting period, the fundamental speed, and the size, as well as the shape of the regulation curve.

My improved mechanism is distinguished by great simplicity, may quickly and inexpensively be manufactured and mounted and, above all, can easily be attended to and adjusted.

Various modifications and changes may be made without departing from the spirit and the scope of the invention, and I desire, therefore, that only such limitations shall be placed thereon as are imposed by the prior art.

I claim as my invention:

1. In a ring spinning machine, in combination, a driving motor, a speed-controlling device for said motor, a builder arm, a transmitting member secured at one end to said builder arm and at the other end to said motor-speed-controlling device, a sheave mounted on said builder arm, a rotatably movable combined crank and sheave, a member adapted to transmit the movement of said sheave on the builder arm to said crank, and a sec-

ond transmitting member secured at one end to said crank and at the other end to the transmitting member that extends from said builder arm to said motor-speed-controlling 5 device.

2. In a ring spinning machine, in combination, a driving motor, a speed-controlling device for said motor, a builder arm, a transmitting member secured at one end to said 10 builder arm and at the other end to said motor-speed-controlling device, a rotatable sheave mounted on said builder arm, a second rotatable sheave, a crank rigidly secured to the second sheave, a chain connecting said 15 sheaves, the axis of rotation of the second sheave being so located that a line perpendicular to the path of movement of the builder arm at its midpoint is tangent to said sheave, a member for transmitting the motion of the first named sheave to said crank, and a second transmitting member secured, 20 at one end, to said crank and, at the other end, to the transmitting member which connects the builder arm to the motor-speed-controlling 25 device.

3. In a ring spinning machine, in combination, a motor, a speed-controlling device for the motor, a builder arm, a sheave on the builder arm, a flexible transmitting member 30 connected, at one end, to a fixed point on the builder arm and, at the other end, to the speed-controlling device, deflecting means for the transmitting member including a sheave having a crank and connecting means between 35 the sheave on the builder arm and the sheave of the deflecting means for controlling the deflection of the transmitting member by the operation of the sheave on the builder arm.

4. In a ring spinning machine, in combination, a motor, a speed-controlling device for the motor, a builder arm, a rotatable member on the builder arm, a flexible transmitting member connected, at one end, to a fixed point on the builder arm and, at the 45 other end, to the speed-controlling device, deflecting means for the flexible transmitting member for further controlling the speed of the motor, said means including a rotatable sheave, a crank fixed to the sheave, connecting means intermediate the crank and the flexible transmitting member, said connecting means being adjustable with reference to the crank, and a connecting member between the sheave and the rotatable member on the 50 builder arm, thereby controlling the deflecting means by the position of said rotatable member.

5. In a ring spinning machine, in combination, a driving motor, a speed-controlling 60 device for said motor, a builder arm, a transmitting cable adjustably secured, at one end, to said builder arm and, at the other end, to said motor-speed-controlling device, adjustable means for controlling the effective length 65 of said transmitting cable and means for lim-

iting the movement of said transmitting cable.

6. In a ring spinning machine, in combination, a driving motor, a speed-controlling device for the motor, a builder arm, a transmitting cable secured, at one end, to the builder arm and, at the other end, to the speed-controlling device for the motor, means controlled by the operation of the builder arm for variably deflecting the transmitting cable 70 to thereby variably control the longitudinal movement of the transmitting cable, means for adjusting the effective length of the cable, and further means for limiting the deflecting movement of the transmitting member to 75 thereby cause a decrease of the speed of the motor.

7. In a ring spinning machine, in combination, a driving motor, a speed-controlling device for said motor, a builder arm, a transmitting cable adjustably secured, at one end, to said builder arm and, at the other end, adjustably secured to said motor-speed-controlling device, means for adjusting the effective 80 length of said cable and means for limiting 85 the movement of said cable.

In testimony whereof, I have hereunto subscribed my name this 29th day of May, 1929, at Berlin-Siemensstadt, Germany.
